UNITED STATES PATENT OFFICE.

LEWIS S. CHICHESTER, OF NEW YORK, N. Y.

SAD-IRON.

Specification of Letters Patent No. 29,863, dated September 4, 1860.

To all whom it may concern:

Be it known that I, LEWIS S. CHICHESTER, of the city, county, and State of New York, have invented certain new and useful Improvements in Sad or Smoothing Irons, the invention being also Applicable to a Tailor's Goose; and I do hereby declare that the following is a full, clear, and exact description of the same, reference being had to the annexed drawings, making a part of this specification, in which—

Figure 1, is a side view of my invention. Fig. 2, a transverse vertical section of the same taken in the line x, x , Fig. 1. Fig. 3, a view of the bottom or face of the iron of the same.

Similar letters of reference indicate corresponding parts in the several figures.

To enable those skilled in the art to fully understand and construct my invention I will proceed to describe it.

A represents the body or main portion of a smoothing iron which may be of the usual form so far as its sides and upper portions are concerned. The face of the iron however is quite different for instead of being a plane surface as hitherto it has a groove a , made all around it near its edge as shown clearly in Fig. 1. This groove a , 30 has rounded edges at both sides as shown at 1, 1, in Fig. 2, while the bottom of the groove may be formed of a gradual curve 2.

The edge 3, of the face of the iron is angular precisely the same as that of an ordinary iron, and the portion of the face designated by 4 which is bounded by the groove a may be a trifle lower than the edge 3. This is not strictly necessary but I consider it preferable. By having the face of the iron thus arranged the fabric is subjected to three different actions in the process of

ironing; to wit, first, that produced by the angular edge 3, which is common to both my invention and the old irons, and which is used for taking out the small folds in the fabric; second, that produced by the flat or smooth surface 4 bounded by the groove a , and, third, that produced by the rounded surfaces 1, at the edges of the groove a .

The rounded surfaces 1, facilitate the rubbing or pressing operation as the iron is moved over the fabric, the face of the iron slides more easily over the surface of the fabric considerably reducing the labor while at the same time the iron is rendered more efficient in its operation.

The handle B of the iron is composed of a wrought iron rod b , which is bent in spiral form as shown clearly in Figs. 1 and 2. The rod b , may be quite small in diameter 60 for the spiral twist forms a handle of sufficient thickness to be conveniently grasped by the hand, at the same time it will be seen that it quickly cools as there is not a large mass of metal to retain the heat and a free 65 circulation of air is allowed all around the rod b . The rod may be bent by properly heating the same and winding it around a mandrel.

Having thus described my invention, I 70 claim as new and desire to secure by Letters Patent as an improved article of manufacture—

A smoothing iron having a hollow spiral self ventilating handle, and the edges of its 75 rubbing surface provided with a groove, and otherwise constructed as herein shown and described.

LEWIS S. CHICHESTER.
